BOTTLE FEEDING MECHANISM FOR
WASHING MACHINES

Archie E. Ladewig, Waukesha, Wis., assignor to
Archie Ladewig Co., Waukesha, Wis., a corpora-
tion of Wisconsin

Application August 9, 1948, Serial No. 43,292

3 Claims. (Cl. 198—24)

1

The present invention relates in general to improvements in automatic article feeders and relates more especially to improvements in the construction and operation of feed mechanisms for automatically delivering bottles or similar receptacles in predetermined order to a washing machine or like apparatus.

Many different types of feed mechanisms intended for the purpose of automatically delivering successive bottles to washers or the like, have heretofore been proposed and used commercially with varying degrees of success. In some of these prior feeders, the dirty bottles are arranged in successive rows which are automatically transferred to the successive rows of receiving pockets of a conveyor which is adapted to transport the receptacles through the various cleansing zones of the washer, and the number of bottles involved in each row varies in accordance with the capacity of the washing installation. These bottle feeds may also be segregated into several classes as to manner of final discharge, in one of which the rows of bottles received from the supply source are finally delivered by gravity into the receiving pockets, while in the other class the segregated successive rows of dirty bottles are pushed horizontally over a support and into these pockets.

While relatively little difficulty is encountered in operation of some of these prior feeders when delivering bottles of identical shape and size; considerable annoyance is had when dealing with odd shaped bottles of diverse sizes, and under the latter operating conditions, most of the prior feeders become jammed and require extensive personal attention in order to keep them operating, thus involving delay and loss of valuable washing time. The prior feed mechanisms embodying gravity discharge are not only very noisy in operation when handling bottles of varying sizes, but they also introduce excessive breakage of glass receptacles; and most of the previous feed assemblages are complicated in structure and rather unreliable in operation, besides lacking ability to automatically and effectively receive the dirty bottles en masse and to remove successive bottles from the supply mass to prearrange them in neat rows of properly spaced individual bottles preparatory to final injection of the rows into the washer pockets.

It is therefore a primary object of my present invention to provide an improved mechanical bottle feeder which obviates all of the objections and operating difficulties of prior devices of this type, and which is therefore exceedingly reliable

2

and safe when subjected to varying operating conditions.

Another important object of the present invention is to provide an improved bottle feed mechanism especially applicable to washing machines having receptacle conveyors provided with successive rows of bottle receiving and transporting pockets, and wherein successive rows of properly spaced bottles are automatically withdrawn from a mass of bottles of diverse shapes and sizes initially resting in upright position upon a supply deck, and are gently and effectively delivered to corresponding rows of receiving pockets.

15 A further important object of this invention is to provide an automatic feed unit for glass bottles or the like, in which the relatively frail and brittle receptacles are rapidly transferred from a source of supply to a delivery zone, rapidly but without shock or excess noise, thus eliminating undesirable breakage of bottles.

20 Still another important object of my invention is to provide an automatic bottle feed for bottle cleansing machines, which is simple, compact and durable in construction, while being adapted to be intermittently actuated directly from the washer drive so as to most effectively deliver bottles of various sizes and shapes to each of the successive carrier pockets of the washer, thereby insuring most efficient functioning and maximum capacity of the receptacle cleansing installation.

25 An additional important object of the invention is to provide a new and useful bottle feeder which may be manufactured, installed and operated at moderate cost for use in conjunction with different types of washing machines, and which will continue to automatically perform its duty without abnormal attention, delay, or danger.

30 A more important specific object of this invention is to provide an improved transferring and guiding assemblage for bottle feed mechanisms, comprising a bottle transfer conveyor having an approximately horizontal bottle supporting deck and a series of laterally spaced bottle segregating partitions for guiding successive rows of bottles being transported by the conveyor toward the delivery end of the feed deck, the partitions being mounted and positioned so as to dispose their lower guiding portions over or above the deck and without intersecting the bottle supporting surface thereof, thus permitting the use of either one or more endless conveyors 35 having a substantially continuous deck surface.

These and other objects and advantages of the invention will be apparent from the following detailed description.

A clear conception of the several features which constitute my present improvements, and of the construction and operation of a typical bottle feed mechanism embodying these features, may be had by referring to the drawings accompanying and forming a part of this specification wherein like reference characters designate the same or similar parts in the various views.

Fig. 1 is a side view of one of the improved feed units associated with the inlet end of a typical bottle washer having rows of receiving and conveying pockets for transporting the successive bottles therethrough, this view showing a row of slightly tilted dirty bottles immediately after having been transferred from the delivery end of the feed deck to the transfer rotor of the feed mechanism;

Fig. 2 is a similar side view of the bottle feeder, but showing the previously slightly tilted row of bottles being positioned in horizontal position upon the final transfer plate of the feed unit;

Fig. 3 is another similar view of the same bottle feeder, but showing the same row of bottles immediately after having been transferred from the final transfer plate into the adjacent row of bottle conveying pockets of the washer;

Fig. 4 is an enlarged transverse section through the support for the bottle segregating partitions;

Fig. 5 is a top view of the improved bottle feed mechanism shown in Figs. 1, 2 and 3, but drawn to a slightly larger scale than in said figures; and

Fig. 6 is a front end view of the same feed mechanism, drawn to the scale of Fig. 5.

While the invention has been shown and described as having been embodied in a typical bottle feed mechanism especially adapted for co-operation with bottle washers such as shown in my Patent No. 2,551,140, granted May 1, 1951, it is not my intention in view of this specific disclosure to unnecessarily restrict the scope or utility of the improved features some of which are obviously more generally applicable to feeders for other types of receptacles; and it is also contemplated that specific descriptive terms employed herein be given the broadest possible interpretation consistent with the disclosure.

Referring to the drawings, the general type of automatic bottle washer to which the improved bottle feed mechanism is especially applicable, comprises a main casing 8 having therein an endless conveyor 9 provided with successive parallel rows of bottle carrier pockets 10 for transporting successive rows of bottles 11 through the several soaking and cleansing zones of the machine. The conveyor 9 may be driven either continuously or intermittently in any suitable and well known manner, and is preferably guided near the feed end of the machine by means of guide plates 12 so as to cause the bottle transporting pockets 10 to travel in approximately horizontal position along a substantially vertical path. All of the foregoing washer elements may be constructed and operated as shown and described in my prior patent above referred to, and constitute no part of the present invention.

The improved bottle feed mechanism forming the subject of this application, consists primarily of an auxiliary feed casing 14 firmly secured to the front end of the main casing 8; conveying means such as one or more endless bands or chains 15 having an upper deck 16 for transport-

ing the dirty bottles 11 en masse toward the relatively advancing run of the conveyor 9; a series of upright bottle segregating partitions 17 supported within the casing 14 entirely above the bottle delivery end of the deck 16 by means of a reciprocable suspension plate 18; a rotor having a series of bottle tilting and transfer disks 19 mounted upon a drive shaft 20 and each provided with a bottle transfer abutment 21 while being revolvable in vertical planes mid-way between adjacent partitions 17; an approximately horizontal stationary bottle guiding and transfer plate 22 for receiving the bottles 11 from the transfer rotor in horizontal position; and an oscillatory transfer bar 24 for periodically sliding the successive rows of horizontal bottles 11 off of the plate 22 and into the adjacent carrier pockets 10.

The major portion of the bottle feeding unit is housed within the auxiliary casing 14 but the front portion of the bottle conveying deck 16 of the feed chains 15 is upwardly open so as to permit the dirty bottles 11 to be deposited en masse and in upright position upon the deck 16 in advance of the partitions 17; and while the conveying means specifically illustrated consists of several simultaneously operable endless bands or chains 15, these may in some cases be combined into a single endless structure. The endless conveying means or chains 15 may be supported upon front and rear pulleys or sprockets 25, 26 respectively, either of which may be driven in any convenient manner so as to advance the upper bottle supporting deck 16 toward the main casing 8; and as shown, the rear sprockets 26 are adapted to be intermittently revolved by a ratchet pawl 27 pivotally mounted upon an arm 28 which is oscillatable upon the sprocket drive shaft 29 by a link 30, and is cooperable with the peripheral notches of a ratchet wheel 31 secured to the shaft 29. The link 30 is pivotally attached to the outer end of another arm 32 secured to the rotor driving shaft 20, and this latter shaft 20 is constantly rotated from the driving mechanism of the main conveyor 9 by means of a belt or chain 33, as shown in the drawings. When conveyor chains 15 are utilized, it is preferable to cause the lower run of the chains to pass through a pan 34 containing soap water as illustrated in Figs. 1, 2 and 3 in order to maintain the chains and sprockets well lubricated at all times.

The bottle segregating and arranging partitions 17 are preferably spaced equi-distant apart and are disposed vertically with their lower guiding portions in close proximity to the deck 16 but without intersecting the bottle supporting surface of the deck. As previously indicated, all of these partitions 17 are suspended from the plate 18 entirely within the feed casing 14; and in order to enable the partitions 17 to most effectively separate and arrange the oncoming dirty bottles into uniform rows, it is preferable to move them back and forth transversely of the direction of advancement of the upright bottles 11. The partition suspension plate 18 is therefore mounted in elongated guides 36 secured within the casing 14, and is reciprocable by means of a bell-crank 37 pivotally secured to the casing wall and having one arm connected to the plate 18 by a rod 38 while its other arm is connected to an auxiliary arm 39 attached to the hub of the pawl carrying arm 28 which is oscillatable upon the shaft 29, by another rod 40, see Fig. 6. With this assemblage, whenever the feed mechanism is operating and the

chains 15 are being intermittently advanced, the partitions 17 will be moved bodily back and forth over the deck 16 and the mass of advancing upright bottles 11 will automatically be divided or separated into neatly arranged successive rows corresponding to the rows of carrier pockets 10, irrespective of the size or shapes of the admitted bottles, and without causing jamming of the entering upright bottles 11.

The bottle transfer rotor for tilting the successive rows of bottles 11 delivered from the deck 16, is also housed within the casing 14, and the bottle tipping and transfer disks 19 of this rotor are rigidly attached to the shaft 20 which is journalled in bearings carried by the side walls of the casing 14. All of the rotor disks 19 are of identical formation, being cam shaped as shown in Figs. 1, 2 and 3, and the rotor is constantly revoluble by the belt or chain 33 so as to cause the disk abutments 21 to periodically revolve upwardly between the adjacent conveyor chains 15 and rearwardly between the rear ends of the adjacent partitions 17. The speed of rotation of the disks 19 is properly timed, so that the disk abutments 21 will pick up the successive rows of bottles 11 delivered from the discharge ends of the intermittently advancing conveyor chains 15 whenever the latter are at rest, and the cam shaped disks 19 thereafter tilt the bottles from upright to horizontal position while advancing them toward the washer pockets 10 and onto the guide plate 22.

The horizontal guiding and transfer plate 22 is likewise housed and secured within the casing 14, and is provided with a series of upper parallel ridges 41 for maintaining the bottles in properly spaced rows for entry into the carrier pockets 10. The oscillatory pusher bar 24 is mounted upon arms 42 swingably suspended from a horizontal shaft 43 mounted in bearings also carried by the upper portion of the casing 14, and the shaft 43 is periodically oscillatable by means of a lever 44 and connection 46 which may be operated at properly timed intervals from the main washer driving mechanism in a well known manner, and as shown in my prior patent. Whenever a row of horizontal bottles 11 is being deposited upon the supporting plate 22 by the rotor disks 19 as in Fig. 2, the transfer bar 24 is retracted and disposed remote from this plate in order to avoid interference with the advancing bottles; but after each row of bottles has been positioned upon plate 22, the pusher bar 24 is promptly swung downwardly and rearwardly so as to slide or push the successive bottle rows gently across the fixed plate 22 and into the successive receiving pockets 10, as illustrated in Fig. 3.

When the improved bottle feeding mechanism has been properly constructed and applied to a washer as hereinabove described, and the washing machine is being operated to advance the main conveyor 9 and bottle transporting pockets 10 along the guides 12, the washer may be constantly loaded by merely placing the dirty bottles 11 en masse and in upright position upon the deck 16 through the opening in the casing 14 above this deck, as depicted in Fig. 5. As the washer conveyor 9 continues to advance the pockets 10, the drive chain 33 constantly rotates the rotor shaft 20 and the disks 19 carried thereby, in a clockwise direction as viewed in Figs. 1, 2 and 3, and also intermittently advances the chains 15 so as to move the deck 16 rearwardly, while at the same time continuously

reciprocating the partitions 17 across the deck 16. The connection 46 also functions to oscillate the pusher bar 24, and all of these movements are timed to properly cooperate with the advancement of the main conveyor 9. The pan 34 should preferably be supplied with soapy liquid into which the lower runs of the chains 15 dip, thereby maintaining the chains 15 and sprockets 25, 26 well lubricated whenever the machine is operating.

The mass of upright dirty bottles 11 deposited upon the conveyor deck 16 is carried rearwardly toward the front edges of the upright segregating partitions 17, and as these partitions move back and forth across the deck 16, they separate the bottles into uniform successive rows of upright bottles 11 which are subsequently advanced by the moving deck 16 toward the transfer rotor. Upon leaving the rear end of the deck 16, each row of bottles is deposited upon the alined disk abutments 21 which move upwardly between the adjacent chains 15, and the bottles are slightly tilted as shown in Fig. 1; and as the transfer disks 19 continue to revolve between the adjacent partitions 17, they further tilt the bottles and eventually deliver them in horizontal position upon the fixed supporting grid or plate 22, as in Fig. 2. After the rotor abutments have passed downwardly through the slots in the plate 22, the bottles will momentarily rest in the troughs formed by the plate ridges 41, whereupon the pusher bar 24 will be lowered and moved rearwardly to slide the successive rows of horizontal bottles 11 across the supporting plate 22 and into the successive rows of carrier pockets 10, as depicted in Fig. 3. This sequence of operations is rapidly repeated, and the successive rows of dirty bottles 11 are thus positively withdrawn from the supply mass resting upon the deck 16, and are transferred to the successive rows of carrier pockets 10, effectively and without shock or loss of time due to jamming.

The laterally moving bottle guiding partitions 17 which are suspended from the constantly reciprocating plate 18, function to effectively segregate the bottle mass into uniform rows, regardless of the shape or size of the bottles 11, and without permitting the advancing bottles to jam and clog the spaces between these partitions. By suspending the partitions 17 so that their lower guiding portions are located above and in close proximity to the transfer deck 16, while avoiding intersection of this deck by the partitions, the deck surface between the partitions may be maintained smooth and devoid of grooves, and one or more conveyors may be utilized to form the deck surface. As shown, several slightly spaced chains 15 are utilized in order to permit the transfer abutments 21 of the rotor disks 19 to pass upwardly between the adjacent conveyor sections; but since the spaces are alined with the rotor disks 19 mid-way between the adjacent partitions 17 they do not objectionably interfere with the bottle support and the gaps may be filled in with fixed strips so as to preserve the continuity of the upper deck surface.

The constantly revolving transfer rotor with its disks 19 and abutments 21 passing between the conveyor chain sections 15, causes the successive bottle rows to be gently removed from the delivery end of the deck 16; and the cam formation of the revolving disks 19 subsequently causes the bottles to be gradually tipped or tilted from upright to horizontal position and deposited in the latter position upon the stationary grid plate

22. The periodically oscillatable pusher bar 24 is thereafter operable to likewise gently slide the successive bottle rows over the plate 22 and into the advancing carrier pockets 10 without shock or excessive noise, thus avoiding bottle breakage and producing quiet functioning of the bottle feed mechanism. The ridges 41 of the plate 22 insure proper guiding of the horizontal bottles 11 while being transferred from the rotor to the pockets 10, and the slots in the plate 22 enable the abutments 21 to pass without interference.

From the foregoing detailed description of the construction and operation of my invention, it will be apparent that I have provided an improved bottle feeding unit which besides being simple, compact and durable in construction, is also automatic and highly efficient in operation. The improved feed mechanism will function effectively with bottles 11 of various sizes and shapes admitted en masse to the deck 16, and the guiding partitions 17 automatically segregate the admitted bottles into successive rows of properly spaced bottles; and the assemblages may therefore be applied to different types of receptacle washing and treating machines. The suspension of these partitions above the transfer deck 17, and the reciprocation thereof laterally of the direction of bottle advancement, are important features of my invention and add to the universal adaptability of the mechanism; and the constantly revolving transfer rotor cooperating with the intermittently advancing feed deck 16 enables rapid operation and effective cooperation with constantly advancing bottle receiving pockets 10. The invention has gone into highly satisfactory and successful commercial use; and the feed mechanism may be manufactured, installed and operated at very moderate cost and with minimum attention.

It should be understood that it is not desired to limit this invention to the exact details of construction and operation of the specific bottle feed mechanism, herein shown and described, since various modifications within the scope of the appended claims may occur to persons skilled in the art.

I claim:

1. In a bottle feeder for a washer having transverse rows of bottle conveying pockets for receiving the bottles in approximately horizontal condition, a horizontal conveyor deck movable to advance bottles resting in upright position thereon toward the successive rows of pockets of the washer, a stationary approximately horizontal bottle transfer plate located above and spaced from the delivery end of said deck but terminating closely adjacent to the pocket rows, a bottle transfer rotor disposed within the space between said deck and said plate and being operable to tilt and transfer the bottles from the delivery end of the deck to the plate remote from the pocket rows, a series of parallel upright bottle guiding partitions spanning said space and said rotor and extending forwardly over said deck and having rear tapered ends converging and extending toward said plate, and a pusher movable downwardly along said tapered partition ends to

engage the tilted bottles deposited upon said plate by said rotor and to inject them into the adjacent pocket rows.

2. In a bottle feeder for a washer having transverse rows of bottle conveying pockets for receiving the bottles in approximately horizontal condition, a horizontal conveyor deck movable to advance bottles resting in upright position thereon toward the successive rows of pockets of the washer, a stationary approximately horizontal bottle transfer plate located above and spaced from the delivery end of said deck but terminating closely adjacent to the pocket rows, a bottle transfer rotor disposed within the space between said deck and said plate and being operable to tilt and transfer the bottles from the delivery end of the deck to the plate remote from the pocket rows, a series of parallel upright bottle guiding partitions spanning said space and said rotor and extending forwardly over said deck and having rear tapered ends converging and extending toward said plate, means for reciprocating said partitions transversely of said conveyor deck, and a pusher movable downwardly along said tapered partition ends to engage the tilted bottles deposited upon said plate by said rotor and to inject them into the adjacent pocket rows.

3. In a bottle feeder for a washer having transverse rows of bottle conveying pockets for receiving the bottles in approximately horizontal condition, a horizontal conveyor deck movable to advance bottles resting in upright position thereon toward the successive rows of pockets of the washer, a stationary approximately horizontal bottle transfer plate located above and spaced from the delivery end of said deck but terminating closely adjacent to the pocket rows, a bottle transfer rotor disposed within the space between said deck and said plate and being operable to tilt and transfer the bottles from the delivery end of the deck to the plate remote from the pocket rows, a series of parallel upright bottle guiding partitions spanning said space and said rotor and extending forwardly over said deck and having rear tapered ends converging and extending toward said plate, means for moving said partitions back and forth over said conveyor deck, and a pusher movable downwardly along said tapered partition ends to engage the tilted bottles deposited upon said plate by said rotor and to inject them into the adjacent pocket rows.
